UNITED STATES PATENT OFFICE.

SIMON MORITZ, OF ST. LOUIS, MISSOURI.

CLOTH-LAYING MACHINE.

1,078,302.

Specification of Letters Patent. Patented Nov. 11, 1913.

Application filed December 20, 1912. Serial No. 737,881.

To all whom it may concern:

Be it known that I, SIMON MORITZ, a citizen of the United States, residing at the city of St. Louis, State of Missouri, have invented a certain new and useful Improvement 5 in Cloth-Laying Machines, of which the following is a full, clear, and exact description, such as will enable others skilled in the art to which it appertains to make 10 and use the same, reference being had to the accompanying drawings, forming part of this specification, in which—

Figure 1 is a top plan view of a cloth laying machine of my improved construction. 15 Fig. 2 is a side elevational view of my improved machine and showing the table on which the machine operates in section. Fig. 3 is a cross sectional view taken approximately on the line 3—3 of Fig. 1. Fig. 4 is 20 an enlarged detail section taken on the line 4—4 of Fig. 2. Fig. 5 is a detail section taken approximately on the line 5—5 of Fig. 2.

My invention relates to new and useful 25 improvements in cloth laying machines, the principal object of my invention being to construct a comparatively simple, inexpensive and easily operated machine which can be readily manipulated by a single operator 30 for arranging layers of cloth one upon the other and face to face in perfectly smooth condition, which arrangement is desirable and necessary where a number of layers of cloth are to be cut into pieces or sections by 35 means of patterns in the manufacture of clothing.

Heretofore, it has been the practice to lay the cloth by hand, which procedure requires the services of two or more operators, and 40 where cloth is thus laid by hand, it is almost impossible to arrange the sections of cloth one upon the other without stretching, which result is very undesirable particularly where the cloth is to be cut up into sections suitable 45 for the manufacture of wearing apparel.

I propose to provide a simple machine with which a single operator can readily arrange in smooth condition and without stretching, layers of goods, the same being 50 arranged face to face and with the front edges of the layers of goods straight and in alignment with each other, thus laying out the goods in proper position for the cutter.

To the above purposes, my invention consists in certain novel features of construc-

tion and arrangement of parts hereinafter more fully described and claimed.

In the construction of the machine as shown, the truck portion comprises a rail 10 on the ends of which are positioned short 60 rails or wheel pieces 11, and arranged for rotation in suitable bearings on the ends of these wheel pieces are shafts 12 which are parallel with the rail 10, and the ends of said shafts are provided with wheels 13 65 which travel upon track rails 14 fixed to the edges of the table 15 on which the cloth is laid. The wheel pieces 11 are connected to the ends of the rail 10 by means of bolts 16 which pass through said wheel pieces and 70 engage the ends of clamping members 17 which latter overlie end portions of the rail 10. Seated in the forward ends of the wheel pieces is a cross bar 18 and adjustably positioned thereon near one end is a plate 19 75 bearing a mark 20 which serves as a guide to enable the operator to lay the goods straight upon the table and with the front edges of the layers of the goods in direct alinement with each other.

Carried by the cross bar 18 is a forwardly and downwardly projecting frame 21, and journaled thereon is a roller 22 beneath which the cloth passes as it is laid upon the table. The purpose of this roller is to lay 85 the cloth in smooth condition without stretching onto the surface of the table or onto the layers of cloth already laid thereon.

Fixed to one of the cross bars or wheel pieces 11 is a handle 23 which is adapted to 90 be engaged by the operator to move the machine lengthwise of the table. The slide which is supported by the truck comprises a rail or bar 24, to the central portion of which is fixed a pair of vertically disposed 95 plates 25, the lower ends of which are bent inwardly so as to engage beneath the rail 10. Journaled between the plates 25 is a roller 26 which bears directly on top of the rail 10, and fixed to one end of the rail 24 is a 100 bracket 27 in which is journaled a roller 28 that bears on top of the rail 10. Journaled in the upper portion of the bracket 27 is a roller 29 which is adapted to form a rolling support for the base of a stand hereinafter 105 described.

The upper portions of the plates 25 are connected by a cross plate 30 and mounted to rotate freely on said cross plate is a disk 110 or bearing plate 31 to which is fixed a rail

32, which latter forms the base of the stand which carries the goods or cloth to be laid by my improved machine.

Passing through the central portion of the rail 32 is a pin 33, the lower end of which is seated in the cross plate 30 and the rail 24. One end of the rail 32 normally bears upon the roller 29 and the opposite end portion of said rail 32 is engaged beneath the jaws of a catch 34, which latter is carried by the end of an arm 35, the same being pivotally mounted on top of the rail 24. A spring 36 is interposed between the rail 24 and the underside of the catch 34, thus normally forcing said catch upward so as to engage the rail 32 and hold the same in alinement with the rails 10 and 24 while the machine is in operation.

Fixed to the ends of the rail 32 are standards 37, in the upper ends of which are journaled short shafts 38, and formed on the inner ends thereof are sockets 39 adapted to receive the wooden roller 40 on which the cloth is wound prior to its delivery to the laying machine. One or both of the shafts 38 are arranged so as to move lengthwise through their bearings in order that the roller 40 can be readily positioned in or removed from the sockets.

30 The means for adjusting the slide 24 and the cloth carrying stand upon the truck and transversely of the table comprises a short shaft 41 which is journaled in a suitable bearing 42 on one end of the bar 24 comprising the slide, and fixed on the outer end of this shaft is a crank handle 43. The inner end of this shaft 41 is threaded and passes through a bracket 44 which is fixed on the corresponding end of the truck frame.

40 When my improved machine is in use, a roll of cloth upon the roller 40 is supported between the standards 37 with the ends of the roller engaged in the sockets 39. The free end of the roll of cloth is brought downward over the cross bar 18 and the plate 19 thereon, said cloth being positioned beneath the roller 22 and attached in any suitable manner to the end of the table 15.

In case the edge of the goods does not coincide with the guide mark 20, the operator manually engages the crank handle 43 and rotates the shaft 41, thereby moving the slide 24 and parts carried thereby upon the truck and transversely of the table, and thus 55 the goods carried by the stand can be shifted until the edge of said goods coincides with the gage mark 20 on the plate 19. As the shaft 41 is rotated, the threaded portion thereof operates through the bearing 44 and 60 as a result the slide 24 is moved upon the cross rail 10 during which time the rollers 26 and 28 ride upon said cross rail 10. After this adjustment has been made, the operator manually engages the handle 23

and moves the machine lengthwise over the table and during such movement the operator, by observing the position of the edge of the goods with respect to the mark 20, can readily tell whether or not the goods are being laid perfectly straight and true upon 70 the table.

During the movement of the machine from one end of the table to the other, the goods unwind from the roller 40 and pass beneath the roller 22 by which said goods are laid 75 evenly and without stretching upon the table. When the opposite end of the table is reached, the operator cuts the goods transversely so as to detach the laid section from the goods carried by the machine, and said 80 machine is now drawn to the head of the table without laying any of the goods thereon. When the machine has been brought to the head of the table, the operator depresses the catch 34 thereby disengaging the cross 85 bar 32 and said cross bar and the supported roll of goods are swung upon the center bearing one half a complete turn, thus reversing the stand and goods end for end. When this action is accomplished, the catch 90 34 is permitted to reengage the cross bar 32, thus maintaining the stand in proper position, and the free end of the goods is now brought down over the cross bar 18 and the plate 19 thereof and the end of said goods is passed 95 beneath the roller 22. The operator now manipulates the slide adjusting means by operating the crank handle 43, thus bringing the edge of the second layer of goods into alinement with the edge of the layer of goods 100 already on the table. The first layer of goods positioned on the table is laid face upward and when the stand and goods carried thereby has been reversed or turned end for end prior to the laying of the second layer 105 of goods, the roll is positioned so that when the second layer is positioned on the first layer, said second layer will be laid face downward, which arrangement is necessary where the goods are cut by pattern and are 110 utilized in the manufacture of wearing apparel. The third layer of goods will be laid face upward and the fourth layer face downward, which arrangement is continued until all of the goods from the roll have been laid. 115

The machine can be drawn lengthwise over the table with comparatively little effort on the part of the operator and by means of the roller 22, the sections or layers of the goods are positioned on the table and upon 120 each other in perfectly smooth condition without stretching and in proper condition for the cutters.

A machine of my improved construction is comparatively simple, can be cheaply 125 manufactured and by its use piece goods can be easily and accurately laid in proper position for cutting.

Where goods are laid out by hand, it is almost impossible to avoid stretching of the goods and it is a comparatively hard matter to get the front edges of the goods perfectly even. These objections are overcome by the use of the machine of my improved construction and said machine requires the services of but a single operator.

It will be readily understood that minor changes in the size, form and construction of the various parts of my improved cloth laying machine can be made and substituted for those herein shown and described without departing from the spirit of my invention.

I claim:

In a machine of the class described, the combination with a table having track rails

on its edges, of a truck, a cloth laying roller journaled in said truck, a member arranged to slide on said truck, means for adjusting the position of the member on said truck, a cloth supporting frame pivotally mounted on the sliding member, a gage plate adjustably mounted on the truck immediately over one end of the cloth laying roller, and a latch on the sliding member for engaging and holding the cloth supporting frame.

In testimony whereof I hereunto affix my signature in the presence of two witnesses, this 17th day of December, 1912.

SIMON MORITZ.
